[57] **CLAIM**

The ornamental design for an earring spring, as shown and described.

DESCRIPTION

FIG. 1 is a front, left, top perspective view of a spring for a clip-on earring showing my design therefor;

FIG. 2 is a top plan view thereof;

FIG. 3 is a side elevational view thereof, the opposite side being an identical mirror image;

FIG. 4 is a bottom plan view thereof;

FIG. 5 is a front elevational view thereof; and,

FIG. 6 is a rear elevational view thereof.
